CLAIM

The ornamental design for a “flow meter end fitting with integral tube connector-version 3”, as shown and described.

DESCRIPTION

FIG. 1 is a perspective view of a flow meter end fitting with integral tubing connector-version 3 showing my new design;

FIG. 2 is a rear perspective view of a flow meter end fitting with integral tubing connector-version 3;

FIG. 3 is a right side elevational view, left side elevational being a mirrored image thereof;

FIG. 4 is a front elevational view thereof;

FIG. 5 is a rear elevational view thereof;

FIG. 6 is a top plan view thereof; and,

FIG. 7 is a bottom plan view thereof.
